COMBINATION TOOTHBRUSH AND TUBE HOLDER

Mildred M. Goodman, Scranton, Pa.

Application March 21, 1950, Serial No. 8,671

Term of patent 3½ years

(Cl. D4—3)

To all whom it may concern:

Be it known that I, Mildred M. Goodman, a citizen of the United States, residing at Scranton, in the county of Lackawanna and State of Pennsylvania, have invented a new, original, and ornamental Design for a Combination Toothbrush and Tube Holder, of which the following is a specification, reference being had to the accompanying drawings, forming a part thereof.

Figure 1 is a front elevational view of a combination toothbrush and tube holder, showing my new design;

Figure 2 is a side elevational view of the same.

I claim:

The ornamental design for a combination toothbrush and tube holder, as shown.

MILDRED M. GOODMAN.
